United States Patent Office

Des. 202,654
Patented Oct. 26, 1965

202,654

PAINTER'S SHIELD OR SIMILAR ARTICLE

Marcus J. Carls, 4436 W. 61st St., Los Angeles, Calif.

Filed Oct. 7, 1963, Ser. No. 76,874

Term of patent 14 years

(Cl. D54—13)

FIG. 1.

FIG. 2.

FIG. 3.

FIG. 4.

FIG. 5.

I claim:

The ornamental design for a painter's shield or similar article, substantially as shown.
